UNITED STATES PATENT OFFICE

JAMES A. WOODS, OF SALT LAKE CITY, UTAH

WAXER AND POLISHER

Application filed July 24, 1930. Serial No. 470,377.

My invention relates to waxers and polishers and has for its object to provide a new and efficient waxing and polishing device which will automatically eject the wax on 5 the floor intermittently as desired and which may then be used to spread the wax and polish the floor thereafter.

A further object is to provide a waxing and polishing device which uses liquid wax in the can in which it is purchased and which can has the usual spring top lid removed therefrom and a substitute closure placed therein to stop or control the flow of fluid therefrom.

15 A still further object is to provide an economical device for spreading wax on a floor and polishing the floor thereafter, which device is so constructed as to allow the operator, by an up and down motion of the handle, to feed just the required amount of wax on the 20 surface being covered, and which handle may be reversed to the other end of the machine and the machine used for polishing without any danger of feeding any wax on 25 the floor, or the person using the device may close the flow of wax from the machine by closing a screw valve.

These objects I accomplish with the device illustrated in the accompanying drawing in which similar numerals and letters of reference indicate like parts throughout the several views and as described in the specification forming a part of this application and pointed out in the appended claims.

35 In the drawing in which I have shown the best and most preferred manner of building my invention, Figure 1 is a side elevation of the device with the handle shown cut away. Figure 2 is a plan view thereof. Figure 3 is a longitudinal section of the base of the device showing the handle engaging the can for forcing the wax therefrom. Figure 4 is a section of the closure cap.

45 In the drawing I have shown the base of my device as a box A, having the top open and having the ends 1 and 2 made thicker than the side walls 3 and 4. The ends of the side walls 3 and 4 are cut away at 5 and the entire bottom surface of the box A and the ends 1 and 2 are encircled with a sheet of

felt 6 or other suitable substance which has sufficient polishing and resilient qualities. The ends of the felt 6 encircle the ends 1 and 2 of the device and are engaged thereover by spring wires 7 and 8, which wires 55 are passed thereover with their end portions curved downwardly and inwardly and engaged with holes cut in the side walls 3 and 4 where they are cut away at 5. The top side of the ends 1 and 2 is provided with a groove 60 9 in which the wire forces the felt and in which groove the wire engages to hold the wire and felt from movement therefrom. A fabric cover is then placed around the felt pad 6 with the end engaged under the wires 65 7 and 8 through an opening 10 left by cutting a central notch from the ends of the pad 6 where it is secured by the wires 7 and 8.

Across the bottom of the said base or box A, I then form a partition 12 which partition has a semi-circular portion cut centrally therefrom leaving a semi-circular collar 13 medially therein, which collar is adapted to fit the bottom side of the neck of a wax containing can B. Through the bottom surface 75 of the base A between the end 1 and the partition 12, I form two spaced apart elongated openings 14 and 15 which openings are separated by a portion 16 which portion has the top side cut to slope down through the openings to act as a distributing gate for the wax 80 which is fed thereon from the can B.

A handle C is provided for the device and is formed and attached to the base A by legs 85 16 and 17 secured pivotally to the base A by pivot pins 18 in each side wall thereof and the legs are then bent toward each other to where they are joined to the handle C by rivets or screws 20. A lever 22 is secured onto the 90 bottom side of the handle C and extends therefrom over the coating can B between the legs 16 and 17. This lever is for pressing down on the top side of the can to force fluids therefrom.

95 The can B is of the usual type of wax holding cans which are on the market filled with liquid wax and is provided with the usual spring held top, and to use the can in my device, I remove the top and replace it with a 100 similar closure top 27, having a flow pipe 29

therethrough. The outer end of the pipe 29 is externally threaded at 31 to receive a screw cap 34 which cap is adapted to be screwed down thereon to close the end of the pipe.

5. The said cap has a port 33 bored through one side thereof and a washer 32 is carried in the cap so that when the cap is unscrewed the wax may flow through the pipe and into the cap and then through the port to the openings

10 14 and 15. The flow may be cut off by screwing the cap onto the pipe closing the end of the pipe in the washer. This provides a means for controlling the flow of wax from the can into the two openings 14 and 15. The inner

15 end 35 of the pipe 29 is turned or curved toward the edge of the can B and is extended sufficient distance to approach the side of the can B when the plug is inserted therein, but leaving sufficient space therebetween to allow the wax from the can to flow into the pipe 29 to allow for complete drainage of the can and for an unhampered flow therefrom.

The operation of my device is as follows:—

20 The person using the device for the first time takes the usual spring held top from the can of wax and replaces it with my closure top with the outlet pipe of the plug adjacent one side of the can. He then places the can in the base by putting the neck 28 of the can into the collar 13 of the partition 12 in the bottom of the can. The screw cap 34 may then be unscrewed on the threads 31 of the pipe 29, opening the port 33 any desired amount, leaving the port 33 open partially or entirely open and the device is then ready for operation. The operator then takes hold of the handle and pushes and pulls the base over the floor, at the time when the base is extended from the operator the full length of the handle, the operator presses down on the handle sufficient to cause the lever 22 to press on the top side of the can B. This forces the side of the can inwardly and, due to the pressure thus created inside the can, forces some of the wax out through the pipe 29 and the port 33 into the two openings 14 and 15 and onto the floor, but as the pad is provided with openings similar to the openings in the base A most of the wax is directed onto the surface of the floor and the pad 6 then distributes it onto the floor as it is passed back and forth thereover.

25 It will be obvious that this device may be used for washing and cleaning floors and for mopping floors by simply using liquid soap in a wax can or similar can and also oil, or dressings for floors may be easily and quickly applied to the floors with this device. The device may be used by the housewife as a dust mop when no oil is desired on the floors.

Having thus described my invention I desire to secure by Letters Patent and claim:

30 1. In a device of the class described the combination of a base; means to hold a wax containing can therein; a closure plug for

said can having a port therethrough; a cap to control the flow of the fluid through said port; openings through said base to allow fluids to pass therethrough; a semi-partition across the bottom of said base to hold the neck of said can; a pad for said base covering the ends and the bottom thereof having openings therethrough in alignment with the openings in said base; spring wires to hold said pad to said base; and a handle for said base made up of two legs secured to a single handle with a central lever between said legs to contact the top side of the wax can when the handle is lowered by the operator to force the fluid therefrom.

35 2. In a device of the class described the combination of a base; a fluid containing can to be inserted therewith; a bifurcated handle for said base; a lever secured between the legs of said handle to engage and press down on the top side of said can when the handle is lowered to force fluid therefrom; and means in the opening of said can to shut off the flow therefrom partially or entirely as desired.

40 3. In a device of the class described the combination of a box shaped base having the top open; a partition across said base near one end thereof having a semi-circular collar formed medially therein; openings through said base between said partition and the near end of said base; a can containing fluids to be inserted into said base with the neck of the can to fit in said semi-circular collar; a closure top for said can having a pipe leading therethrough, with the inner end of the pipe curved toward the side wall of said can and having the outer end threaded to receive a cap; a cap to be screwed over said pipe, adapted to close said pipe as desired; a port through the side of said cap and a bifurcated handle pivoted to said base having a lever between the legs of said handle to engage the side of said can when the handle is lowered.

45 4. In a device of the class described the combination of a wax containing can; a closure for said can comprising a centrally perforated expansion and contraction type cap, having a pipe passed through said perforation and secured in said lid with the inner end of said cap turned down toward one side of the can; a cap to be screwed onto the end of said pipe to control the flow therethrough, said cap having a port through one side thereof to be opened or closed by screwing the cap in or out on the pipe; means to hold said can in a waxing device; and means to press the side of said can to force wax therefrom.

50 5. In a device of the class described the combination of a wax containing can secured in a suitable polishing base; an expansion and contraction closure for said can; a pipe passed through said closure having the inner end bent to near one side of the can; a cap for the open end of said pipe having a port through one side wall, said port to be opened or closed

partially or wholly, by the movement of the cap on the pipe; and means by up and down motions of the handle of the polishing base to force the wax from the can by contact with the side wall of said can.

5 In testimony whereof I have affixed my signature.

JAMES A. WOODS.
